VULCANIZER

Albert W. Ferre, Wellesley, and Charles E. Blanchard, Randolph, Mass., assignors to B. F. Sturtevant Company, Boston, Mass.

Application March 28, 1942, Serial No. 436,576

7 Claims. (Cl. 18-6)

This invention relates to vulcanizers and relates more particularly to vulcanizers for rubber covered wires.

It is the practice in vulcanizers for rubber covered wires to pass the wires through a plurality of parallel vertically extending tubes and to supply superheated steam into the tubes for supplying the heat necessary for vulcanization of the rubber. In prior vulcanizers of this type, air heated by gas fired units was supplied into pipes around and spaced from the above mentioned tubes, the heated air preventing heat losses in the superheated steam for maintaining it in gaseous form. Disadvantages of such vulcanizers were that the gas fired air heaters were expensive and provided fire hazards.

A feature of this invention resides in utilizing steam instead of heated air for preventing heat losses in the superheated steam.

Another feature of this invention resides in utilizing ejector type air seals for preventing the escape of the superheated steam with its chemical vapors into the apparatus rooms by drawing in room air.

Objects of the invention are to simplify vulcanizers for rubber covered wires and the like; to reduce their cost, and to improve their efficiency.

The invention will now be described with reference to the drawings, of which:

Fig. 1 is a side elevation with portions in section of a vulcanizer tower embodying features of this invention;

Fig. 2 is an enlarged view illustrating how the air seal at the lower end of one of the vertical tubes of Fig. 1, is provided;

Fig. 3 is an enlarged view of one of the vertical tube assemblies of Fig. 1 without the insulation, and illustrates how the superheated steam is introduced, and how the steam for preventing heat losses in the superheated steam is supplied, and

Fig. 4 is an enlarged view of the diffuser of Fig. 3, for introducing the superheated steam.

As is known, the wires to be vulcanized pass vertically through the centers of the tubes 5 while during their passage through the tubes the rubber which previously is deposited thereon, is vulcanized by the application of superheated steam to the surface of the rubber.

With reference to Figs. 1 and 2, the tubes 5 have placed therearound the larger tubes 6 and the insulation 7 is placed around the tubes 6. In Figs. 3 and 4 the insulation 7 is not shown.

As illustrated by Figs. 3 and 4, superheated steam is supplied into the inner tubes 5 through

the diffuser consisting of the perforated supply pipe 30 and the enlarged connecting pipe 7 around the pipe 30. The high velocity of the superheated steam is reduced so that it cannot displace the rubber covered wire which is moving vertically and centrally through the tube 5. The supply pipes 30 are thus connected to the tubes 5 at points about one-eighth the distance from the lower ends of the outer tubes 6 to their upper ends.

The steam for maintaining the superheated steam in gaseous form is supplied into the outer tubes 6 through the inlets 8 (Fig. 3) and is drawn with the condensate out through the outlets 9 and returned through the usual traps to the steam boiler. This steam circulates completely around the tubes 5 through which the superheated steam is applied, and by preventing the escape of heat from the superheated steam, maintains it in gaseous form while it is in the vulcanizer.

The superheated steam may be supplied at about five pounds per square inch pressure at a temperature of about 400° F. and the heating steam may be supplied at a pressure between 180 and 250 pounds per square inch and at a temperature corresponding thereto.

As illustrated by Figs. 1 and 2, each of the tubes 5 has adjacent its lower end, connected thereto the ejector fittings 10 which include the nozzles 4. The fittings 10 are connected by the piping 12 to the header 13, which in turn, is connected to the inlet of the fan 14. The outlet of the fan 14 is connected as shown by Fig. 1, to the ducts 15 and 16 which communicate with the outdoor atmosphere.

The upper ends of the tubes 5 have connected thereto the fittings 17, which may be fittings similar to the previously described fittings 10, connecting the interior of the tubes by piping to the header 18 which in turn is connected to the inlet of the fan 19. The fan 19 discharges through the duct 20 into the outdoor atmosphere. The connections of the fittings 17 to the header 18, and of the header 18 to the fan 19, are similar to the corresponding connections illustrated by Fig. 2.

In operation superheated steam is supplied into the tubes 5, and heating steam into the tubes 6 as previously described, for providing the vulcanizing heat. The lower fan draws in room air through the open lower ends of the tubes 5, this air having its velocity increased by passage through the nozzles 4. The suction of the fan prevents the superheated steam in the pipe 5 from exhausting into the apparatus room,

through the open lower ends of the tubes 5 and causes it with the room air, to be drawn into the fan and exhausted into the atmosphere, the room air thus providing an air seal.

An important feature of the fitting 10 with its nozzle 4 is that the condensate from the superheated steam instead of dripping onto the floor of the apparatus room as occurred in previous vulcanizers, is prevented by the air jets through the nozzles 4 from falling through the lower ends of the pipes 5 and is caused to be drawn by the action of the fan into same and to be forced by the fan into the outlet duct 16 (Fig. 1) from which it may be withdrawn through the connection 21. This condensate contains chemicals as a result of the contact of the superheated steam with the chemically treated wire, and it is important that it be prevented from escaping from the vulcanizer.

The upper fan 19 in a similar manner draws room air through the open upper ends of the pipes 5 together with the superheated steam from the pipes 5 and forces the mixture through the duct 20 into the atmosphere. Since there is no necessity for recovering the condensate in the fittings 17, they need not contain nozzles such as the nozzles 4 in the fittings 10, and may be ordinary T pipe fittings.

Through the superheated steam being drawn off by the fans, adjacent both ends of the tubes 5 not only is it maintained in movement and thus in gaseous form, but more uniform heating and resultant vulcanizing is accomplished. The equipment for accomplishing this also, as described, provides air seals for preventing the superheated steam and the chemical drippings therefrom, from escaping into the apparatus room.

While one embodiment of the invention has been described for the purpose of illustration, it should be understood that the invention is not limited to the exact apparatus and arrangements of apparatus described since modifications thereof may be suggested by those skilled in the art without departure from the essence of the invention.

What is claimed is:

1. A vulcanizer for rubber covered wire and the like, comprising a plurality of upwardly extending tubes through which the wire passes, means for admitting superheated steam into said tubes at points intermediate the ends thereof, said tubes having open upper and lower ends, means including a fan adjacent the upper ends of said tubes for drawing in air through said upper ends forming an air seal and for drawing in superheated steam from said tubes, and means including a fan adjacent the lower ends of said tubes for drawing in air through said lower ends and for drawing in superheated steam from said tubes, said last mentioned means including means for preventing the passage of moisture from said lower ends.

2. A vulcanizer for rubber covered wire and the like, comprising a plurality of upwardly extending tubes through which the wire passes, means for admitting superheated steam into said tubes at points intermediate the ends thereof, said tubes having open upper and lower ends, means including a fan adjacent the upper ends of said tubes for drawing in air through said upper ends forming an air seal and for drawing in superheated steam from said tubes, and means including a fan adjacent the lower ends of said

tubes for drawing in air through said lower ends and for drawing in superheated steam from said tubes, said last mentioned means including means for preventing the passage of moisture from said lower ends and for causing the moisture to be drawn into said last mentioned fan.

3. A vulcanizer for rubber covered wire and the like, comprising a plurality of upwardly extending tubes through which the wire passes, means for admitting superheated steam into said tubes at points intermediate the ends thereof, said tubes having open upper and lower ends, means including a fan adjacent the upper ends of said tubes for drawing in air through said upper ends forming an air seal and for drawing in superheated steam from said tubes, and means including a fan adjacent the lower ends of said tubes for drawing in air through said lower ends and for drawing in superheated steam from said tubes, said last mentioned means including converging air nozzles through which the room air from said lower ends passes for preventing the passage of moisture from said lower ends and for causing the moisture to be drawn into said last mentioned fan.

4. A vulcanizer for rubber covered wire and the like, comprising a plurality of upwardly extending tubes through which the wire passes, means for admitting superheated steam into said tubes at points intermediate the ends thereof, said tubes having open upper and lower ends, outer tubes around said tubes, means for admitting steam into and removing steam and condensate from, said outer tubes, means including a fan adjacent the upper ends of said tubes for drawing in air through said upper ends forming an air seal and for drawing in superheated steam from said tubes, and means including a fan adjacent the lower ends of said tubes for drawing in air through said lower ends and for drawing in superheated steam from said tubes, said last mentioned means including means for preventing the passage of moisture from said lower ends.

5. A vulcanizer for rubber covered wire and the like, comprising a plurality of upwardly extending tubes through which the wire passes, means for admitting superheated steam into said tubes at points intermediate the ends thereof, said tubes having open upper and lower ends, outer tubes around said tubes, means for admitting steam into and removing steam and condensate from, said outer tubes, means including a fan adjacent the upper ends of said tubes for drawing in air through said upper ends forming an air seal and for drawing in superheated steam from said tubes, and means including a fan adjacent the lower ends of said tubes for drawing in air through said lower ends and for drawing in superheated steam from said tubes, said last mentioned means including means for preventing the passage of moisture from said lower ends and for causing the moisture to be drawn into said last mentioned fan.

6. A vulcanizer for rubber covered wire and the like, comprising a plurality of upwardly extending tubes through which the wire passes, means for admitting superheated steam into said tubes at points intermediate the ends thereof, said tubes having open upper and lower ends, outer tubes around said tubes, means for admitting steam into and removing steam and condensate from, said outer tubes, means including a fan adjacent the upper ends of said tubes for drawing in air through said upper ends forming an air seal and for drawing in superheated steam from said tubes.

and means including a fan adjacent the lower ends of said tubes for drawing in air through said lower ends and for drawing in superheated steam from said tubes, said last mentioned means including converging air nozzles through which the room air from said lower ends passes for preventing the passage of moisture from said lower ends and for causing the moisture to be drawn into said last mentioned fan.

7. A vulcanizer for rubber covered wire and the like, comprising a plurality of upwardly extending tubes through which the wire passes, means including diffusers for admitting superheated steam into said tubes at points intermediate the ends thereof, said tubes having open upper and lower ends, outer tubes around said tubes, means

5 for admitting steam into and removing steam and condensate from, said outer tubes, means including a fan adjacent the upper ends of said tubes for drawing in air through said upper ends forming an air seal and for drawing in superheated steam from said tubes, and means including a fan adjacent the lower ends of said tubes for drawing in air through said lower ends and for drawing in superheated steam from said tubes, said last mentioned means including converging air nozzles through which the room air from said lower ends passes for preventing the passage of moisture from said lower ends and for causing the moisture to be drawn into said last mentioned fan.
